COLLAPSIBLE JUG SUPPORT

Frank Y. Ikeda, Buena Park, Calif.

Application May 8, 1959, Serial No. 55,844

Term of patent 7 years

(Cl. D58—26)

I claim:

The ornamental design for a collapsible jug support, substantially as shown.
